UNITED STATES PATENT OFFICE.

ARTHUR ROBERTS, OF EVANSTON, ILLINOIS, ASSIGNOR, BY MESNE ASSIGNMENTS, TO CHICAGO TRUST COMPANY, TRUSTEE, OF CHICAGO, ILLINOIS, A CORPORATION.

COKE-OVEN DOOR AND THE LIKE.

Application filed October 31, 1919. Serial No. 334,704.

To all whom it may concern:-

Be it known that I, ARTHUR ROBERTS, a citizen of the United States, residing at Evanston, in the county of Cook and State 5 of Illinois, have invented certain new and useful Improvements in Coke-Oven Doors and the like, of which the following is a specification.

The present invention has to do with certain improvements in the construction of coke oven doors and the construction and operation of mechanism for seating and extracting the same. The construction of door herein disclosed is intended particularly for 10 use in connection with by-product coke ovens and the like, although it will presently appear that the features of invention herein disclosed are not necessarily limited to use in this particular type of door, but in many 15 cases may be used in connection with doors intended for other uses. However, in order to simplify the illustration and description of the present invention, and in order to clearly illustrate or exemplify one application 20 of the features of the present invention, I have illustrated and described the same as used in connection with a coke oven construction.

Bearing the foregoing in mind, it will be 25 understood that these coke oven doors are large and heavy and become very hot during the operation of the oven. It is, therefore, very desirable to so construct the door and associate therewith suitable handling 30 mechanism so that the door can be properly seated or removed from time to time during the operation of the oven.

It is customary to provide in connection 35 with a bench of coke ovens, suitable mechanism for pushing the completed coke from the ovens, which mechanism is usually so constructed that it may be moved into different positions in order to operate on the different ovens. In some cases, I avail myself 40 of the presence of such machine for the purpose of handling the coke oven doors in seating or removing them, in which case suitable mechanisms are provided in or in conjunction with the pushing mechanism for 45 extracting and seating the doors. In such cases, I so construct the coke oven door itself 50 that the said mechanism may be readily and securely attached to the particular door which it is desired to manipulate.

55 In order that the construction and opera-

tion of the doors themselves may be more readily understood, and in order that their relation to such door seating and extracting mechanism may be more readily understood, I have illustrated and shall describe the door 60 of the present invention in some cases in association or combination with a suitable type of pushing and door extracting mechanism, or a portion of such mechanism, but I wish to have it clearly understood that 65 in so doing, I do not limit myself to the use of the door of the present invention in connection with such mechanism.

I will also state at this point that it is 70 very customary to provide at the back side of the bench of ovens a coke guide which may be moved from point to point along the bench of ovens to guide the coke into a car or a carriage as it is delivered from any particular oven. The door seating and extracting mechanism which I have illustrated, and will describe as being in combination with a pushing mechanism may also be used in association and combination with such coke guide or the like, and, therefore, will 75 be understood that the door seating and extracting mechanism may be used in combination with any suitable form of carriage or the like as desired.

On account of the high temperature existing with the coking or carbonizing chamber 80 it is necessary to provide a special lining for the door. Otherwise the said door must be water cooled, or it will be rapidly burned away. Even where a special lining is provided, it may become desirable to renew the 85 said lining from time to time. It is, therefore, very desirable to so construct the door that the lining may be readily inserted or removed from the door frame. One of the 90 objects of the present invention is to provide a construction of door having a permanent frame and a removable lining, which lining may be readily inserted into or removed from the frame in sections.

Other objects and uses of the invention 95 will appear from the detailed description of the same which consists in the features of construction and combinations of parts hereinafter described and claimed.

In the drawings:

Figure 1 shows a front elevation of a door embodying the features of the present invention, and showing the same in position at the end of an oven;

Figure 2 shows a section taken on the line 2-2 of Figure 1 looking in the direction of the arrows;

Figure 3 shows an enlarged detailed elevation of the upper portion of the door illustrated in Figures 1 and 2;

Figure 4 shows a horizontal section taken on the line 4-4 of Figure 3 looking in the direction of the arrows;

10 Figure 5 shows an enlarged fragmentary vertical section taken on the line 5-5 of Figure 3, looking in the direction of the arrows;

15 Figure 6 shows an enlarged fragmentary elevation of the door and locking devices;

Figure 7 shows a plan view corresponding to Fig. 6;

20 Figure 8 shows a section taken on the line 8-8 of Fig. 7 looking in the direction of the arrows;

25 Figure 9 shows a vertical side elevation of a portion of a pusher mechanism and the door seating and extracting mechanism which may be conveniently used in conjunction with the door of the present invention;

Figure 10 shows a plan view corresponding to Figure 9;

20 Figure 11 shows a fragmentary side elevation of the door seating and extracting beam of the mechanism shown in Figures 9 and 10;

25 Figure 12 shows a vertical central section through the mechanism of Figure 11, in its relation to the door, and in the position 30 which it occupies just before being raised into engagement with the door elements;

35 Figure 13 is a fragmentary view corresponding to Figure 12 with the exception that the door seating and extracting mechanism has been raised into full engagement 40 with the door elements; and

Figure 14 shows a horizontal section taken on the line 14-14 of Figure 3, looking in the direction of the arrows.

45 Referring now to the drawings, I have illustrated the present invention as being applied to a coke oven construction in which there are provided adjacent to the various oven openings the buckstays 15 and 16. 50 While these buckstays constitute in themselves a convenient means for attachment of the coke oven doors so as to hold the latter in position, it will be understood that they are in no sense an essential portion of the 55 door construction.

I will also state that for purpose in convenience for illustration, I have shown in the drawings a typical door such as may be used at the pusher end, said door being provided with a leveller opening in its upper portion through which a suitable levelling tool may be manipulated preparatory to the coking operation. This levelling opening is, however, not essential as regards many 60 features of the present invention and in fact

it is unnecessary to use a levelling opening in connection with the doors at the coke end.

A generally rectangular frame work or casing 17 is provided around each door opening, the same constituting a portion of the fixed structure. This rectangular casing is not essential to the door construction, although it constitutes a convenient portion of the permanent structure, when used. When such casing is provided it may have 70 its inner portion 18 flanged or tapered inwardly in the manner clearly illustrated in Figure 4.

75 It may be provided with peripheral lug portions 19 against which may be engaged 80 the brackets 20, which are normally attached to the buckstays 15 and 16 and serve to hold the door frame permanently in position. The door frame is generally provided with a shoulder seat 21 against which 85 the removable door or a portion thereof may engage.

80 The door includes a rectangular frame member 22 of contour and size proper to close the opening. This door frame member 90 95 22 is generally of metal such as cast iron, but may be made of other materials if desired.

90 The frame member 22 has the bottom cross piece 23, the top cross piece 24, and in case a leveller door is provided it may have the intermediate cross piece 25. It will thus be seen that a more or less rectangular structure is provided within which 100 may be located and secured a suitable lining for the door. This is the lining designated in its entirety by the numeral 26. This lining is generally made up of blocks or bricks of silica or other highly refractory material, and the lining generally projects inward a substantial distance beyond the edge portion of the frame member 23 as is clearly evident from Figures 2, 5, 105 12 and 13.

110 Examination of Fig. 14 will reveal the fact that the side portions 29 and 30 of the door frame member 22 are beveled so that the blocks of silica or the like may be wedged into place. It will also be observed from comparison particularly of Figs. 2 and 115 14 that the door lining is made up of a number of courses each comprising three blocks, 31, 32 and 33 and that the central block 32 is in each case of keystone shape so that when wedged into position it serves to force 120 the side blocks securely into position.

125 In order to hold the lining blocks in position and in order to give the outside face of the door a finished appearance, I have provided a plate 34 which may be bolted or otherwise secured to the outer edges of the door frame after the blocks of the lining have been set into place.

130 In some cases it will be found desirable to provide supplemental cross pieces 35 and

- 36 at various points within the height of the door so as to distribute the weight of the refractory lining. This construction will also make it possible to distribute the 5 expansion which will occur in the lining so that the minimum amount of movement of the lining blocks will occur between the conditions of maximum and minimum temperature. This fact is illustrated particularly in 10 Fig. 2 wherein will be observed the expansion joints 37, 38 and 39 at the upper ends of the respective piles or stacks of lining blocks.
- By reference to Figs. 1, 12 and 13 in particular, there will be observed inserts 40 and 15 41 at the two sides of the door casing. These inserts are in the nature of expansion joints and when they are used the door casing may be made of upper and lower sections designated 17^a and 17^b respectively, the two sections being kept in alignment in any suitable manner, as by means of dowel pins 42 in the manner clearly evident from examination of 20 Figs. 12 and 13. The insert blocks may be of wood or any other suitable material.
- 25 As previously explained the construction illustrated in the drawings of this case shows a leveller door 43, since the particular construction illustrated in the drawings is that for use at the pusher side. When such 30 leveller door is used it may be of any suitable construction, but the particular form illustrated and which I will now describe in detail will be found to possess simplicity combined with ease and facility of manipulation in the opening and closing movements.
- This particular leveller door is of dish shaped formation so that its edge portion may rest or seat against the door frame. A 35 lug 44 is inserted in the front face of the leveller door and is provided with an internal socket 45. A bifurcated lever 46 has its bifurcations pivoted to the side portion of the door frame by a pin 47, and the construction illustrated in Figs. 3 and 4 will 40 be found very desirable for this purpose. Said construction includes the bifurcations 48 and 49 on the end portion of the bar 46, which bifurcations receive between them the lug 50 on the door frame.
- 45 The lug 44 is slidably entered within a recess or socket in the back face of the lever 46. Nevertheless, the arrangement is such that at all positions in normal operation of the device the door 43 will be supported by the lever 46 by means of said lug 44.
- 50 A pin 51 is journaled within the lever 46 and said pin has at its inner end a collar 52 which works against the back face of the lever 46 or works within a recess or socket in said lever. Said pin 51 has its inner end threaded to engage the threads of the socket 45 so that by rotating the pin 51 in the one direction or the other the lug 44 and consequently the door 43 will be moved back and forth 55 with respect to the lever 46. A hand wheel 53 serves as a convenient element for effecting such rotation.
- When the leveller door is to be locked closed the free end 54 is supported and then the lug 44 and door 43 are forced towards the door frame by proper rotation of the hand wheel 53. When the leveller door is to be opened, the free end 54 of the lever 46 is to be disengaged so as to permit the entire mechanism to be swung to one side on the pivot 47. A convenient construction for quickly locking or unlocking the free end of the lever is that which I will now explain:
- Referring particularly to Figs. 3 and 5 there will be observed a lug 55 projecting outwardly from the door frame. Said lug has a socket or notch 56 for the accommodation of the free end 54 of the lever 46. A locking member 57 is pivoted to the lug 55 at the point 58. Said locking member 57 has an inwardly facing shoulder 59 which, when the locking device is thrown down into the position of Fig. 5, engages the outer face of the free end 54 to lock the lever in closed position. Upon raising the locking device 60 65 by means of a hook 60 conveniently provided for that purpose, and which may be engaged by a bar or in any other suitable manner, the lever 46 will be released.
- The front side of the locking device is provided with a bevel surface 61 so that if perchance the locking device should be in closed position when the lever 46 is swung shut, the free end of the lever will strike said bevel surface and cause the locking device 100 to lift and permit the free end of the lever to enter the recess 56. At its lower back corner the locking device is provided with another lug 62 so that when the free end of the lever strikes said lug, it will knock 105 the locking device down again into closed position.
- I will now explain the construction illustrated for the purpose of locking the door itself in position within the door casing or at the end of the oven. For this purpose reference may be had particularly to Figs. 6, 7, 8, 12 and 13. At a convenient position on the door, I provide one or more locking devices, and preferably two, equally spaced 110 in the height of the door. Each of these locking devices is conveniently carried on a bracket or the like 63 secured to the door frame or to the cover plate 34 which was previously mentioned.
- Within each of the brackets 63 is pivoted or journaled a locking device designated in its entirety by the numeral 64. Each said locking device includes a cross bar 65 the end portions 66 and 67 of which are adapted to lockingly engage suitable stationary elements; and the locking device also includes one or more arms 68 and 69 the inner ends of which are journaled in the brackets 63.
- In those cases in which buckstays such as 130

15 and 16 are provided they serve as a convenient support for brackets 70 and 71 which brackets are provided with lugs or the like 72 and 73 against which the end portions 66 5 and 67 of the locking device may engage. The parts are preferably so related that when the locking device is dropped or forced down into the closed position of Fig. 8 it will wedge against the lugs or stops and 10 thus insure a tight seating of the coke oven door.

I will now explain in detail one form of mechanism which may be used for seating or extracting the door, although it will be understood that any other suitable form of such mechanism might be used for this purpose. The mechanism illustrated comprises a portion of the leveling mechanism. For simplicity in illustration and description, I 20 will state that the pushing and leveling mechanism may travel on rails 74 and 75 which extend along parallel to the bench of ovens so that the entire device may be brought into position adjacent to any particular coke oven door. This mechanism includes also a pair of standards 76 and 77 within which is slidably mounted a beam 78, the same ordinarily travelling on rollers 79 and 80. A motor 81 serves to move the 30 beam 78 back and forth through the medium of gearing 82 and 83 and a rack 84. The machine may be caused to travel back and forth on the rails 74 and 75 by means of a motor 85 in conjunction with gearing 86, a shaft 87, and gears 88 and 89.

A head member 90 is connected to the end portion of the beam 78. This head member is conveniently in the form of a rectangular box like structure and includes the side 40 members 91 and 92. Within the head member 90 is movably mounted a frame having side pieces 93 and 94 (see Figs. 10 and 13) and cross pieces 95 and 96 extended between the frame members 93 and 94. It is thus 45 evident that there is provided an interior rectangular frame within the outer frame, the outer frame being secured to the beam 78 and the interior frame being vertically movable with respect to the outer frame. 50 A shaft 97 is journaled with respect to the side members 91 and 92 of the outer frame in the journals 98 and 99. This shaft 97 carries a bevel pinion 100 which meshes with a bevel gear 101 journaled with respect to the outer frame. This bevel gear 101 in turn 55 carries an up-right sleeve 102 threaded on its interior and engaging the lower threaded end of a vertical pin 103. The upper end of this pin is suitably guided as it moves up and down, and the pin is also shouldered at 104 to engage a cross piece 105 which extends between the members 93 and 94 of the inside frame. The pin 103 is held against 60 rotation in any suitable manner. It will 65 now be evident that upon rotating the shaft

97, which rotation of the shaft may be readily accomplished by means of a hand wheel 106 the inside frame will be raised or lowered with respect to the outside frame.

On the face of the door are provided one or more sockets 107 and 108 which may be engaged by pins on the door seating and extracting mechanism so as to carry the door back and forth as the seating and extracting mechanism is manipulated. For this purpose I provide the brackets 109 and 110 which project forwardly from the cross pieces 95 and 96 of the inside frame, which brackets carry the projecting pieces or lugs 111 and 112 corresponding in position to the sockets 107 and 108. It will now be evident that upon moving the door handling mechanism into position and then raising the inside frame by proper manipulation of the hand wheel 106 the lugs 111 and 112 will engage the sockets 107 and 108 so as to take the load of the door. Thereafter, the door handling mechanism may be backed away so as to extract the door, and thereafter, the entire machine may be caused to travel along the track way to one side or the other.

It will be evident that before the door can be removed it is necessary to disengage the locking devices. This is done by swinging them upwardly into the position illustrated for example, in Fig. 13. For this purpose I conveniently locate the sockets 107 and 108 adjacent to the locking devices, and in such case it is possible to provide lugs or the like 113 and 114 on brackets 109 and 110 so that the locking devices will be disengaged simultaneously with the engagement of the lugs 111 and 112 with their respective sockets.

While I have herein shown and described only a single embodiment of the features of my invention, still it will be understood that I do not limit myself to the said embodiment except as I may do so in the claims.

I claim:

1. A coke oven door comprising, in combination, a rectangular metallic open frame, the inner surfaces of the side members of said frame being closer together adjacent to the back side of the frame than the front side thereof, a horizontal partition extending across the opening of the frame, a series of courses of blocks of refractory material seated within the frame, the blocks of each course extending beyond the back side thereof, each course including side blocks and a wedge-shaped block located between them, the courses above the partition resting upon and being supported by said partition, whereby expansion of the blocks is divided and does not accumulate beyond said partition, and means for preventing removal of the blocks at the front side of the door, substantially as described.
2. A coke oven door comprising, in com-

bination, a rectangular metallic open frame, a series of courses of blocks of refractory material located within said frame, the back ends of said blocks projecting beyond the back face of the frame, a cover plate on the front face of the frame serving to prevent removal of the blocks in that direction, a pair of brackets secured to said cover plate in vertical alignment with each other, and a locking device pivotally mounted within each of said brackets, each locking device including a pair of swinging arms and a cross member carried by the outer ends of said arms, the end portions of said cross member being suitable for engagement with stationary locking abutments, substantially as described.

3. The combination with a coke oven door, of a lifting and locking device therefor comprising in combination a downwardly facing socket reaching outwardly

from the face of the door, a pair of arms pivotally mounted with respect to the face of the door at the sides of said socket, a cross member joining together the door ends of said arms, and suitable abutment engaging surfaces in conjunction with the end portions of said cross member, whereby when the arms and cross member reach outwardly from the door said portions may engage suitable locking abutments, and whereby a lifting tool placed beneath the socket and the cross member and provided with upwardly facing lugs in line with the socket and the cross member may engage first the cross member and then the socket in succession as said tool is raised to thereby first unlock the door and then carry the weight of the door by successive operations, substantially as described.

ARTHUR ROBERTS.
